TYPEWRITING MACHINE

William O. Michelsen, Woodhaven, N. Y., assignor to Royal Typewriter Company, Inc., New York, N. Y., a corporation of New York

Application October 1, 1938, Serial No. 232,888

14 Claims. (Cl. 197—102)

This invention relates to typewriting machines, and more particularly to keys for such machines. Keys embodying the invention may, however, be applied to finger-operated members of other machines, such as adding machines, computing machines, and the like.

It is desirable that such keys be neat in appearance, formed of easily manufactured and readily assembled parts, and capable of giving long service with comfort to the operator and without becoming loose or otherwise losing efficiency. An object of the present invention is to provide a key having these desirable characteristics.

Another object is to provide a key including a mounting part or key cup secured to a key lever and a disk positioned to be engaged by the operator's fingers and being firmly connected to the cup in a manner to eliminate possibility of the disk's becoming loose in service.

Another object is to provide a key including a key cup and a disk of firm transparent material held firmly in the cup by snap-fastening interlocking means.

Other objects will become apparent from a reading of the following description, the appended claims, and the accompanying drawing, in which:

Figure 1 is a top plan view of a key embodying the invention in one form;

Figure 2 is a vertical sectional view taken on the line 2—2 of Figure 1;

Figure 3 is a vertical sectional view taken on the line 3—3 of Figure 1;

Figure 4 is a horizontal sectional view taken on the line 4—4 of Figure 2;

Figures 5, 6, 7, 8, and 9 are vertical sectional views similar to Figure 3 and each showing a different embodiment of the invention;

Figure 10 is a group view showing in separated relation the parts of which the Figure 9 embodiment is composed; and

Figure 11 is a perspective view of a key cap ring.

Among the several constructional forms of the invention shown for the purposes of illustration, Figures 1 to 4 inclusive show a portion only of a key lever A, which may be of the usual form and which serves to mount a key assembly generally designated B. The assembly includes a base cup C comprising a bottom 1 and an annular outer wall 2. A washer 3 disposed within the cup is provided with a slot 4 registering with a slot 5 in the cup bottom 1, the two slots receiving a key lever shank 6 which is peened as at 7 to secure the key lever, the cup, and the washer to-

gether. The washer may be formed with raised flanges 8 to serve a purpose to be described.

A disk 9 of cardboard or the like displaying a character or characters 10 on its upper face is positioned in the cup and rests upon the flanges 8. A disk 11 of firm, substantially unyielding, transparent, shatter-resisting material is positioned in the cup and over the character disk 9, and is snugly embraced by the cup wall 2.

In accordance with one feature of the invention, the cup outer wall 2 which preferably is of metal is slightly springy and is formed at its top edge with a circumferential ridge 12 which extends inwardly toward the axis of the cup and is received by a circumferential recess 13 formed in the peripheral surface of the disk 11. The ridge 12 and recess 13 are correspondingly shaped so as to provide a snap-fastening frictional interlocking or interengaging connection directly between the cup and the transparent disk. In the form shown, the ridge 12 and recess 13 are rounded in transverse section, making it possible to force the disk 11 downwardly into the cup in a manner to spring the cup wall 2 outwardly until the ridge 12 enters the recess 13 forming the snap fastening referred to above. To facilitate the introduction of the disk 11 into the cup, the peripheral surface portion of the disk below the recess 13 may be tapered as indicated at 14. The resulting assembly is permanently tight and neat in appearance, it being noted that the top edge of the cup wall substantially merges with the marginal upper surface portion of the transparent disk.

In order that the disk 11 may be readily removed from the cup, the bottom of the cup preferably is provided with one or more apertures 15 adapted to accommodate a tool projected inwardly from outside the cup and pushed against the bottom of the character disk 9 so as to force the latter and the transparent disk 11 out of the cup, this being possible because of the springiness of the cup outer wall 2. The apertures 15 extend straight through the cup bottom wall, the axes of the apertures being substantially perpendicular to the cup bottom. Thus the tool may project through the cup bottom substantially perpendicular thereto and perpendicular to the disk 9 for applying ejecting pressure to the disks 9 and 11 in a direction substantially parallel to the cup wall 2.

In order to assure a firm interlocking connection between the cup 2 and the transparent disk 11, it is desirable that the relative diameters of the circumferential ridge 12 and the re-

15

cess 13 be such as to require the exertion of a considerable force to insert the disk into the cup. Consequently the disk must be capable of withstanding considerable pressure without shattering or chipping. The material best suited for forming the transparent disk for use in a construction as described has been found to be "Lucite," a methyl methacrylate plastic. This material is crystal-clear, is about half as heavy as common glass, is strong and durable, and possesses marked resistance to chipping or shattering. It is, however, firm, and a disk of the proportions shown in Figures 1 to 4 when formed of this material will be substantially unyielding as compared to other materials such as rubber and some other molded plastics. Properties of this material rendering it especially adapted for such use are further described in the co-pending application of Bernard Joseph Dowd, Serial Number 232,863, filed October 1, 1938.

The relative separating movement between the peripheral surface of the disk 11 and the cup wall 2 is effected mainly by outward springing of the cup wall, which, although preferably of metal and thus relatively hard, is capable of the necessary outward movement.

The key assembly B^a shown in Figure 5 differs from the key assembly B previously described in that, in the assembly B^a, the ridge 12^a is located intermediate the top and bottom limits of the wall 2^a of the cup C^a, and the circumferential recess 13^a of the disk 11^a is positioned accordingly, so that, when the ridge and recess are in interlocking relation, the top of the wall 2^a will substantially merge with the marginal upper surface of the disk 11^a. The disk 11^a also differs from the disk 11 of the assembly B in that it is not tapered corresponding to the taper 14 of the disk 11 in the assembly B. The bottom 1^a of the cup C^a is the same as the bottom 1 of the cup C. The other parts of the assembly B^a are identical with corresponding parts in the assembly B, and are designated by reference characters the same as those designating identical parts in Figures 1 to 4.

The assembly B^b shown in Figure 6 differs from the assembly B^a shown in Figure 5 in that in the assembly B^b of the ridge 12^b of the cup 2^b of the cup C^b and the recess 13^b of the transparent disk 11^b are so relatively positioned that the disk extends somewhat above the top edge of the cup wall 2^b. The assembly B^b further comprises a key cap ring 16 which fits over the cup wall 2^b and is provided with an inwardly directed flange 17 which preferably is tapered off in thickness so as to merge substantially with the marginal upper surface of the transparent disk 11^b. Ears 18 formed integrally with the cap ring 16 are turned under the bottom 1^b of the cup. The other parts of the assembly B^b are identical with corresponding parts of the assembly B^a (Figure 5), and accordingly are designated by reference characters the same as those applied to the identical parts in the assembly B^a shown in Figure 5.

The assembly B^c shown in Figure 7 is similar to the assembly B shown in Figures 1 to 4 with the exception that the transparent disk 11^c having the circumferential recess 13^c is convex on its lower face rather than being flat as in the assembly B, and the character disk 9^c accordingly is curved to conform to the convexity of the bottom of the disk 11^c. Other parts identical with corresponding parts of the assembly B are designated by reference characters the same as

those designating the identical parts in Figures 1 to 4 inclusive.

The assembly B^d shown in Figure 8 differs from the assembly shown in Figures 1 to 4 in that the cup C^d comprises a bottom 1^d and a side 5 wall 2^d provided with a ridge 12^d which is deformed inwardly, so that its upper inner surface portion is inclined upwardly-inwardly toward the axis of the cup. The recess 13^d in the periphery of the transparent disk 11^d is angular in transverse section, and has a circumferential surface 18^d inclined to correspond with the inclination of the inner surface of the ridge 12^d. In this form the transparent disk is provided with a marginal portion 20^d above the recess 13^d, and extending over and covering the top of the cup wall 2^d. The bottom peripheral edge portion of the disk 11^d is tapered downwardly-inwardly as at 14^d to facilitate insertion of the transparent disk into the cup. Other parts of the assembly B^d are identical with corresponding parts of the assembly B, and therefore are designated by reference characters the same as those designating the identical parts in the assembly B shown in Figures 1 to 4 inclusive. The assembly B^d shown in Figure 8 is such that the entire finger-engageable portion of the assembly is comprised by the transparent disk, which entirely covers the key cup.

In the assembly B^e shown in Figures 9 and 30 10, a cup C^e supported on a key lever A comprises a cup bottom 1^e and a plane annular outer wall 2^e having no ridge corresponding to the ridges described with reference to the forms previously referred to. The cup C^e and a washer 3^e are joined to the key lever A as at 4, 5, 6, and 7 in the same manner as described with reference to Figures 1 to 4, and a character disk 9 is supported within the cup resting upon the flanges 8 of the washer 3. A key cap ring 16^e fits snugly 40 over the cup and is provided with a flange 17^e which extends into a circumferential recess 13^e in the transparent disk 11^e, thus retaining the parts in assembled relation with the cooperation of ears 18^e integral with the cap ring and extending under the cup bottom 1^e.

The showing in the drawing of the inward extent of the cup wall ribs or ridges may be considered as somewhat exaggerated for clear illustration. The ribs or ridges are of such size or 50 inward extent that the snap action interlocking connection between the cup walls and disks can be effected because of a slight springiness of the ribs or ridges and/or the cup walls.

All of the assemblies disclosed are of neat appearance, are formed of easily manufactured and readily assembled parts, and are capable of giving long service with comfort to the operator without becoming loose or otherwise losing efficiency. The embodiments of the invention disclosed are preferred, but changes may be made in the construction and arrangement of the parts without departing from the invention as defined in the claims.

I claim:

1. In a key of the character described, the combination of a base cup having an annular outer wall formed with means projecting inwardly towards the axis of the cup, said inwardly projecting means being slightly springy; and a 70 disk of firm shatter-resisting material positioned in the cup, the periphery of said disk being snugly embraced by said annular wall and being recessed to receive said inwardly projecting means.

2. In a key of the character described, the combination of a base cup having a hard annular outer wall formed with a circumferential ridge projecting inwardly towards the axis of the cup, said ridge being slightly springy; and a disk of firm shatter-resisting material positioned in the cup, the periphery of said disk being snugly embraced by said annular wall and being circumferentially recessed to receive said inwardly projecting ridge. 5
3. In a key of the character described and equipped to display a character, the combination of a base cup having a hard annular outer wall formed with a ridge projecting inwardly towards the axis of the cup, said ridge being slightly springy; and a disk of firm, substantially unyielding, shatter-resisting, transparent material positioned in the cup so as to cover the displayed character, the periphery of said disk being embraced by said annular wall and having a recess which receives said ridge to lock the disk in the cup. 10
4. In a key of the character described, the combination of a base cup having an annular outer wall formed with a ridge projecting inwardly towards the axis of the cup, said ridge being slightly springy; a character disk supported in the cup and a disk of firm transparent material positioned in the cup over the character disk, the periphery of said transparent disk having a recess which receives said ridge to lock the disk in the cup. 15
5. In a key of the character described, the combination of a base cup having an annular outer wall formed with a ridge projecting inwardly towards the axis of the cup, said ridge being slightly springy; a character disk supported in the cup and a disk of firm transparent material positioned in the cup over the character disk, the periphery of said transparent disk having a recess which receives said ridge to lock the disk in the cup, the bottom of said cup having an aperture adapted to accommodate a tool extended in from outside the cup to bear against the character disk for forcing the disk out of said cup. 20
6. In a key of the character described, the combination of a base cup having an outer wall; a disk of firm transparent material positioned in the cup; and springy interengaging means on said wall and the periphery of said disk providing a snap fastening between said cup and disk. 25
7. In a key of the character described, the combination of a base cup having an outer wall; a disk of firm transparent material positioned in the cup; and springy interengaging means on said wall and the periphery of said disk providing a snap fastening between said cup and disk, the bottom of said cup having an aperture adapted to accommodate a tool extended in from outside the cup to forcibly eject said disk from said cup. 30
8. In a key of the character described, the combination of a base cup having a bottom and a wall substantially perpendicular to the bottom; and a disk positioned in said cup and normally retained therein by said wall, the bottom of said cup being provided with an aperture adapted to accommodate a tool extended in from outside the cup to forcibly eject the disk from the cup, said aperture extending straight through the cup bottom with its axis substantially perpendicular thereto, whereby the tool may project through the cup bottom substantially perpendicular to said bottom and said disk for applying disk- 35
- ejecting pressure in a direction substantially parallel to said cup wall. 5
9. In a key of the character described, the combination of a metallic base cup having an outer annular wall; a disk of firm, transparent, non-shatterable molded plastic material positioned in the cup; and snap action interengaging means integral respectively with said cup wall and the periphery of said disk providing a direct frictional interlock between said cup and disk. 10
10. In a key of the character described, the combination of a base cup having an annular outer wall formed along its upper edge with an annular rib extending inwardly toward the axis of the cup; and a disk of firm, shatter-resisting material positioned in the cup and being embraced by said cup outer wall, the upper peripheral edge portion of said disk being formed with a circumferential recess receiving said annular rib and cooperating therewith to provide a direct snap fastening between said cup and disk, said rib and recess being correspondingly shaped in transverse section and said rib being springy whereby said disk may be forced into and out of its fastened position in said cup. 15
11. In a key of the character described, the combination of a base cup having an annular outer wall formed intermediate its top and bottom limits with an annular rib extending inwardly toward the axis of the cup; and a disk of firm, shatter-resisting material positioned in the cup and being embraced by said cup outer wall, the peripheral edge of said disk being formed with a circumferential recess receiving said annular rib and cooperating therewith to provide a direct snap fastening between said cup and disk, said rib and recess being correspondingly shaped in transverse section and said rib being springy whereby said disk may be forced into and out of its fastened position in said cup, the top of said cup outer wall and the contiguous top surface portion of said disk being substantially flush with each other. 20
12. In a key of the character described, the combination of a base cup having an annular outer wall formed with an annular rib extending inwardly toward the axis of the cup; a disk of firm, shatter-resisting material positioned in the cup and being embraced by said cup outer wall, the peripheral edge of said disk being formed with a circumferential recess receiving said annular rib and cooperating therewith to provide a direct snap fastening between said cup and disk, said rib and recess being correspondingly shaped in transverse section and said rib being springy whereby said disk may be forced into and out of its fastened position in said cup; and a cap ring snugly embracing said cup wall and having a flange extending inwardly over the top edge of said wall, the top surface of the flange being substantially flush with the marginal top surface of the disk. 25
13. In a key of the character described, the combination of a base cup having an annular outer wall the inner upper edge portion of which is inclined upwardly-inwardly toward the axis of the cup; and a disk of firm, shatter-resisting material positioned in the cup, the peripheral edge of said disk being formed intermediate its top and bottom limits with an annular recess angular in transverse section and a surface of said recess being inclined correspondingly to the inclination of said inner upper edge portion of said cup wall, said recess receiving said inwardly inclined portion of the cup wall to provide a di- 30
- 75

rect snap fastening between the cup and disk, the disk having a marginal portion above said recess extending over the top of the cup wall and having a downwardly-inwardly bevelled peripheral bottom edge.

14. In a key of the character described, the combination of a base cup having an annular outer wall; a disk of firm, shatter-resisting material positioned in the cup, the upper peripheral edge portion of said disk extending above the top

of the cup wall and being formed with a circumferential recess; and a key cap ring fitting the outside of said cup wall snugly and having at its top an inturned flange received by said recess and providing therewith a snap fastening 5 between said disk and ring, the top of said ring being substantially flush with the marginal top portion of said disk.

WILLIAM O. MICHELSSEN. 10
